United States Patent Office.

F. R. SMITH, OF BENNINGTON, VERMONT.

Letters Patent No. 64,588, dated May 7, 1867.

IMPROVED BLIND-SLAT FASTENING.

The Schedule referred to in these Letters Patent and making part of the same.

TO ALL WHOM IT MAY CONCERN:

Be it known that I, F. R. SMITH, of Bennington in the county of Bennington, and State of Vermont, have invented a new and improved Blind-Slat Fastening; and I do hereby declare that the following is a full, clear, and exact description thereof, which will enable others skilled in the art to make and use the same, reference being had to the accompanying drawings, forming part of this specification, in which—

Figure 1 is an inner view of a blind with my improvement applied to it.

Figure 2 is a vertical section of the same, taken in the line $x x$, fig. 1.

Similar letters of reference indicate like parts.

This invention relates to a new and improved fastening to be applied to a window-blind to hold the slats in a closed or partially closed state, and prevent them when closed from being opened on the outer side of the blinds when the latter are shut.

A represents a window-blind, and B a series of slats, fitted in it as usual, so that they may be turned to let in or exclude the light, as may be required; the several slats being connected by a rod, C, so that they may all be moved or turned simultaneously. These parts, being constructed and arranged in the usual way, do not require a special description. D represents a cam, which is attached to the lower cross-piece a of the blind-frame by a pin or pivot, b. This cam is simply a wheel, having the pin or pivot b passing eccentrically through it, the wheel having a pin or handle, c, projecting from it.

This cam D is directly under the rod C of the slats B, so that the periphery of the cam will bear against the lower end of the rod, and it will be seen that by turning the cam D the rod C will be raised or shoved upward, the portion of the edge of the cam which is the furthest from the pin or pivot b bearing against the rod when the slats are fully closed, and the cam holding the same in a closed state, in fact locking them, as the cam is not accessible from the outer side of the blind when the latter is closed. The cam D may be constructed of either wood or metal, and it is prevented from turning casually by having the pin or pivot b draw the cam snugly against the lower cross-piece a of the blind-frame.

I claim as new, and desire to secure by Letters Patent—

The cam D, applied to the blind-frame to serve as a fastening for the slats, substantially as herein shown and described.

F. R. SMITH.
